UNITED STATES PATENT OFFICE.

FRANK J. PIOCH, OF CRESTON, IOWA.

HOT-AIR FURNACE.

SPECIFICATION forming part of Letters Patent No. 742,062, dated October 20, 1903.

Application filed April 11, 1903. Serial No. 152,157. (No model.)

To all whom it may concern:

Be it known that I, FRANK J. PIOCH, a citizen of the United States, and a resident of Creston, in the county of Union and State of Iowa, have invented a new and Improved Hot-Air Furnace, of which the following is a full, clear, and exact description.

My invention relates to hot-air furnaces and to analogous heating appliances, my more particular object being to increase the efficiency and controllability of the draft and to produce certain improvements in construction.

Reference is to be had to the accompanying drawings, forming a part of this specification, in which similar characters of reference indicate corresponding parts in all the figures.

Figure 1 is a central vertical section on the line 1 1 in Fig. 2 of a hot-air furnace embodying my invention. Fig. 2 is a horizontal section upon the line 2 2 in Fig. 1 looking in the direction of the arrow. Fig. 3 is a fragmentary section upon the line 3 3 in Fig. 2 looking in the direction of the arrow. Fig. 4 is a side elevation of the arm used for controlling a portion of the draft by the opening and closing of the furnace-doors. Fig. 4^a is a rear elevation of the closure-lid and its immediate connection, and Fig. 5 is a section on the line 5 5 in Fig. 1 looking in the direction of the arrow.

An annular base 1 is provided with lugs 2 and with radial arms 2^a. Mounted upon this base 1 is a casing 3, provided with a top 4, having hot-air pipes 5 connected therewith in any preferred manner. The cool-air inlet is shown at 6. An ash-box 7, provided with a top 8, is disposed within the bottom of the casing. The door of the ash-pit is shown at 9 and closes the aperture 10. The fire-pot is made in sections 11 12, provided with radial lugs 13 14, the section 12 being provided at its top with an annular flange 15, into which fits the bottom of the fire-dome 16. The top of this dome is rounded at 16^a into the form of a cupola. A square passage 17 is provided for the purpose of feeding fuel into the fire-pot in the usual manner. A plurality of tubular elbows 18 are integrally connected with the fire-dome and are of the shape indicated best in Figs. 1 and 3. Mounted upon several of these elbows are tubes 19, spaced apart, as indicated in Fig. 2. At 20 is a conical mem-

ber constructed of metal and closed at its top, as indicated in Fig. 1. This member rests at 20^a upon one of the elbows 18. 55

21 is a hollow member, partially flattened at its bottom, as indicated in Fig. 5, and connected by a joint 22 with the square passage 17. The top of the tubular member 21 is provided with an appropriate joint 21^a, to be connected with a pipe 25. The several tubes 19 are similarly provided with joints 23, whereby they may be connected with the several tops of the elbows 18. A number of curved tubular passages 25 are connected with the respective tops of the tubes 19 and the tubular member 21. These tubular passages 25 terminate at 26 within the cylinder 27, being thereby caused to converge to a common point above the fire-dome, and a small pipe 28 leads off 70 laterally from this point of convergence.

A rocking damper 29 is pivoted at 30 and is provided with a lug 31, which is engaged by a rod 32, provided with lugs 33 and with a handle 34, whereby the damper 29 may be 75 adjusted to any desired degree by merely lifting the handle 34 and moving the same in or out, as desired. A rod 35, provided with a handle 36, is connected with a rocking damper 37, this damper being disposed immediately 80 adjacent to the central or cupola outlet 38 of the fire-dome.

A pipe 39 is connected at 40 to the cylinder 27 and is of the sinuous shape indicated in Fig. 1. This pipe normally carries the smoke 85 and gases of combustion directly upward then laterally in a direction to the right and thence downward and into the smoke-pipe. Connected to the end of sinuous pipe 39, by means of a joint 41, is a smoke-box or check-draft 42, provided with a closure-lid 43, this lid being provided with slots 44 45 for the rods 35 32, enabling the same to be manipulated without opening the closure-lid 43. This lid is pivoted at 46 upon the smoke-box or check-draft 42 near the lower end of the smoke-pipe 47, the smoke-pipe being mounted, by means of a joint 48, upon the smoke-box 42. 95

The furnace-door proper is shown at 49 and is pivoted at 50, so as to be free to swing in the usual manner. Mounted rigidly upon this door and movable therewith is an arm 51, provided at its free end with an adjustable bearer 52, the same being radially mov-

able and secured in position by an adjustable bolt 53. The door 49 is provided with a handle 51^a and with the usual draft accessory 54, this draft accessory being mounted upon the 5 central pivot 55 in the usual manner. The square passage 17 is provided with an aperture 56, opening into the tubular member 21, and a small inner door 57 is hinged at 58 and is free to partially obstruct the passage 56.

10 The closing of the door forces the bearer 52 into engagement with the inner door 57, causing the same to occupy the position indicated in Fig. 1, and thereby to partially obstruct the draft otherwise passing up into the tubular member 21. When, however, the door 49 is open, the inner door 57 swings downwardly and into its vertical position. The object of this movement is to prevent a sudden gust of flame and hot gases from passing out of the 15 furnace-door upon the same being opened. The idea is that the opening of the furnace-door causes the inner door 57 to open abruptly, thereby starting up a vigorous draft through the passage 56 and tubular member 21, thus 20 averting the flame, which might otherwise flash out of the furnace-door.

25

The general draft of the furnace may be regulated for four different purposes and for all of these purposes may be controlled by 30 means of the handles 34 36. By running these handles out through the smoke-box 42, as above described, the necessity to open any part of the furnace is obviated. The rods 32 35 lie directly in the path of the smoke 35 and hot gases, so that there is no need for any other passages through the casting, which might allow some of the gases to escape.

In order to start the fire, I generally open both of the dampers 37 and 29. This gives 40 the fire a free escape to the chimney and promotes the greatest draft possible. After the fire begins to burn briskly I close the damper 29, leaving the damper 37 open. This causes the flames and hot gases to travel upward through the central or cupola passage 38 and to pass up into the pipe 39, to thence pass in a lateral direction downward to the smoke-box 42 and thence pass upward into the smoke-pipe. The sinuous path thus pursued enables the stove to throw out more 45 heat than when both dampers are open, as at first described. Suppose now that on account of bad weather or of a bad draft in the chimney the fire burns with difficulty. The 50 proper way to remedy this is to close the damper 37 and open the damper 29. The flames then travel upward through the dome 16 into the cupola 16^a, whence they spread outwardly and downwardly, passing into the 55 elbows 18 and up through the tubes 19 and 21, thence through the tubular members 25 to a common point immediately above the damper 37, thence through the pipe 28 to the smoke-box and to the smoke-pipe. A smaller 60 portion will in this case pass through the

pipe 39, or nearly all of the flames and hot gases will pass through the short pipe 28. By this arrangement the flames and hot gases have considerable travel and will keep the furnace well heated. The fourth and last 70 way, and which is preferable under normal conditions, is to close both dampers. The flames and hot gases then pursue the paths of maximum length, passing first up into the cupola 16^a, thence outwardly and downwardly 75 into the elbows 18, thence upwardly through the several tubular passages and downwardly into the cylinder 27, thence upwardly into the pipe 39 and through a sinuous path to the smoke-box 42, whence they 80 make their escape into the smoke-pipe. This gives the furnace maximum heating capacity.

It will be observed that the short pipe 28 and the long and sinuous pipe 39 virtually constitute a bifurcated offtake for the flames 85 and gases of combustion.

Having thus described my invention, I claim as new and desire to secure by Letters Patent—

1. In a hot-air furnace, the combination of 90 a fire-dome, a plurality of tubular passages connected therewith and converging to a common point, an offtake connected with said passages, said offtake having two members, and means controllable at will for obstructing 95 one of said members.

2. In a hot-air furnace, the combination of 100 a fire-dome, a plurality of tubular passages connected therewith and converging to a common point, an offtake connected with said passages, said offtake having two members, and a manually-controlled damper connected with one of said members.

3. In a hot-air furnace, the combination of 105 a fire-dome, provided with an outlet, a damper connected with said outlet, a plurality of tubular passages connected with said fire-dome and converging to a common point, above said outlet, an offtake connected with said tubular passages, said offtake having 110 two tubular members, and a manually-controlled damper mounted within one of said passages.

4. In a hot-air furnace, the combination of 115 a fire-dome, mechanism connected therewith for directing the flames and hot gases to a point disposed above said dome, a bifurcated offtake for directing said flames and hot gases to a chimney, said offtake having two members, one being straight and the other 120 comparatively sinuous, and means controllable at will for governing the capacity of said straight member.

In testimony whereof I have signed my name to this specification in the presence of 125 two subscribing witnesses.

FRANK J. PIOCH.
